Int. Cl. D7—02

U.S. Cl. D7—128

FIG. 1

FIG. 2

FIG. 1 is a front perspective view of a portable microwave oven showing our new design with the oven interior lighted.

FIG. 2 is another front perspective view similar to that of FIG. 1, but with the oven interior unlighted.

The bottom wall and back wall are flat and substantially plain. In other words, the present invention is related to the front wall of a portable microwave oven.

We claim:

The ornamental design for a portable microwave oven or similar article, as shown and described.
